UNITED STATES PATENT OFFICE.

FRANK D. CLAPPER, OF ALTUS, OKLAHOMA.

ELECTRIC SWITCH.

1,264,898.

Specification of Letters Patent. Patented May 7, 1918.

Application filed February 21, 1916. Serial No. 79,677.

To all whom it may concern:

Be it known that I, FRANK D. CLAPPER, a citizen of the United States, residing at Altus, in the county of Jackson and State 5 of Oklahoma, have invented certain new and useful Improvements in Electric Switches, of which the following is a specification.

My invention relates to electrical switches and has particular reference to new and useful improvements in combination switches, the primary object of the invention being to provide a combination switch for controlling one or more electrical circuits independently or collectively which is simple in construction, cheap to manufacture, strong, durable and effective in operation.

Another object of my invention is to provide a device of the class above described in which means is embodied for controlling 20 from a single source of electrical energy a plurality of work circuits independently or collectively, means being provided on the switch for indicating when the circuits are open or closed.

With the above and other objects in view my invention resides preferably in the construction, combination and arrangement of parts as set forth here and hereafter in the specification and illustrated in the accompanying drawings in which:—

Figure 1. is a plan view of my improved switch, showing the work circuits diagrammatically;

Fig. 2. is a side elevation of the same, 35 showing the circuits diagrammatically;

Fig. 3. is a transverse sectional view taken on the line 3—3 of Fig. 1 looking in the direction of the arrow;

Fig. 4 is a longitudinal sectional view 40 taken on the line 4—4 of Fig. 1 looking in the direction of the arrows.

Fig. 5 is a fragmentary, enlarged perspective view of one of the contacting heads employed in my invention.

Similar reference characters designate 45 corresponding parts throughout the various views of the drawings.

In the drawings, in which the preferred embodiment of my invention is illustrated 50 I provide a casing indicated in its entirety

by the numeral 1 having a bottom 2, side walls 3 and 4 and end walls 5 and 6. The bottom, side and end walls are lined with an insulating material of any desired character designated 7.

My invention embodies particularly two or more circuit closing elements and corresponding terminals for engagement thereby to close a plurality of circuits. This structure preferably includes a supporting bracket 8 mounted on the base 2 and having a binding post 9 or like connecting means associated therewith, for maintaining said bracket in position and to serve as connecting means for one conductor 10 carrying current from one side of a source of electrical energy, such as battery or the like 11. The bracket 8 is provided with an aperture 12 adjacent the upper extremity and axially thereof. The circuit closing members of 70 my invention include preferably a plurality of members, in the present instance, two in number, having tubular bearing portions 13 and 14 arranged in telescopic relation and independently rotatable, the inner of the 75 tubular bodies having a bearing shaft 15 extending from the rear end thereof and journaled in the opening 12. The opposite extremities of the tubular members 13 and 14 are supported by means of an insulating 80 bearing sleeve 16 mounted in an opening 17 formed in the wall 6 of the housing 1. The sleeve 16 preferably extends practically throughout the length of the outer tubular member 14 in order to prevent accidental 85 contact therewith. The outer tubular member 14 is preferably shorter than the tubular member 13, and an insulating manipulating cap 18 is carried thereby, a similar cap 19 being mounted on the tubular member 13. 90 It is of course to be understood that the caps are rigidly carried by the tubular members 13 and 14. The tubular members 13 and 14 are provided on their inner extremities with 95 enlargements or contact heads 20 and 21 respectively, a plurality of circuit closing pins 22 and 23 radially extending from said heads. As shown to advantage in Fig. 5 in the present arrangement of the device the radially extending pins are four in num- 100

ber, three of the pins being arranged at 90° apart, the intermediate pin being arranged at a 45° angle. In Fig. 5 I have illustrated in perspective one of the circuit closing heads, and in this instance the head 20 showing to advantage the preferred arrangement of the circuit closing pins. It will be noted that certain of the pins extend from diametrically opposite points on the periphery 5 of the head 20 and the remaining pins are, respectively, at a 45° angle and a 90° angle relative the pins first mentioned. The head 21 is formed similarly to the head 20 and has a corresponding number of circuit closing pins arranged in a similar manner. Between the heads 20 and 21 is disposed a spacing washer 24 to maintain the tubular members in fixed relation. A washer 25 is also disposed between the bracket 8 and the 10 head 20, said washer coacting with the sleeve 16 to maintain the heads against longitudinal movement.

I provide a plurality of circuit terminals arranged in sets, in the present instance 25 there being a set of 3 for the coaction with the head 20 and designated A, and a second set B for coaction with head 21. The set A includes in the present instance three binding posts designated 26, 27 and 28. The set 30 B includes a similar number of binding posts 29, 30 and 31. The binding posts mentioned are mounted so that the inner extremities thereof project adjacent the path of travel of the pins 22 when the heads are 35 rotated for closing and opening circuits in a manner hereinafter set forth. In order to provide yieldably connecting means for each of the binding posts mentioned I provide spring members 32 rigidly mounted at 33 on 40 the insulating material 7, having their free extremities positioned adjacent to and between the contacting pins 22 and 23 and the binding posts. Each of the spring members 32 is identical in construction, there being 45 one provided for each of the binding posts. In this way the binding posts do not come in direct contact with the pins 22 and 23 but a yieldable connection is afforded by virtue of the interposing of the spring members 50 between the binding posts and said pins.

Each of the binding posts are connected to one conductor on each of a plurality of external circuits designated in Fig. 1, a, b, c, d, e, and f. In the present instance incandescent lamps are shown in the work circuits, the return wire of each of the circuits mentioned being connected to a common return conductor 34.

A plurality of members or letters may be 60 placed on the caps 18 and 19 whereby to indicate in a given position what lamps are lighted so that a person desiring to connect lamps of several circuits simultaneously may do so without the lamps being visible.

In operation assuming that it is desired to 65 light the lamps in the circuits b, c, and f, the head 21 is rotated by means of the cap 18 until the pins which extend from diametrically opposite points on said head come in contact with the binding posts 29 and 31 at 70 which time the circuits b and f will be energized, thereby lighting the lamps in said circuits. At this time the pins of the set 23 carried by the head 21 which extend at 90° relative the diametrically extending pins 75 22 will be in contact with the binding posts 30 thereby closing the circuit c. As shown in Fig. 1 the lamps in the circuits b, c and f are lighted, the lamps in the circuits a, d, and e being extinguished. As shown in Fig. 1 80 the pins 22 of the head 20 are in a neutral position, none of the circuits controlled thereby being energized. When it is desired to energize any one of the work circuits a, b, c, d, e or f that pin of the sets 22 and 23 85 which extends at a 45° angle relative the remaining pins of a set is brought into contact with any one of the binding posts of the sets a and b, in this manner closing the circuit with which the pin contacts. In this position none of the remaining pins of a given set will be in contact with any of the binding posts, therefore maintaining all of the work circuits deenergized with the exception of the one which it is desired to energize. It 90 will be seen that by providing a multiplicity of heads 20 and 21 and corresponding sets of binding posts a number of circuits may be controlled. It will be noted that by the provision of the spring members 32 a quick 95 break of the circuit controlled is assured, thereby eliminating arcing at the contact points.

From the above description taken in connection with the accompanying drawings it 100 is thought that a clear and comprehensive understanding of the construction, operation and advantages of my invention may be readily gathered, and while I have shown and described the same as embodying a 105 specific structure I desire that it be understood that I may make such changes therein 110 which do not depart from the spirit and scope of the invention as claimed.

Having thus described my invention what 115 I claim and desire to secure by Letters Patent is:

A switch including a casing having a dielectric lining, a plurality of circuit terminals mounted upon the bottom and sides of the casing, a dielectric supporting sleeve carried by an end wall of the casing, a pair of sleeves concentrically mounted in the dielectric sleeve, each of said last mentioned sleeves having an enlarged head the heads 120 being spaced apart from one another, a supporting shaft in the inner one of the sleeves, a bracket support for the end of the shaft,

said bracket forming one terminal of an external circuit, turning heads on the ends of the last mentioned sleeve, insulating washers between the heads and the bracket support, and a plurality of contact pins on each of the heads at irregular intervals apart; certain pins being adapted to engage certain circuit terminals, depending on the positions

of said heads, thus closing selected external circuits ending at the circuit terminals. -10

In testimony whereof I affix my signature in presence of two witnesses.

FRANK D. CLAPPER.
